UNITED STATES PATENT OFFICE.

CHARLES A. SHERWIN, OF MUSKOGEE, OKLAHOMA.

DOOR-LOCK.

1,288,234.

Specification of Letters Patent.

Patented Dec. 17, 1918.

Application filed July 25, 1918. Serial No. 246,745.

To all whom it may concern:

Be it known that I, CHARLES A. SHERWIN, citizen of the United States, residing at Muskogee, in the county of Muskogee and State of Oklahoma, have invented certain new and useful Improvements in Door- Locks, of which the following is a specification, reference being had therein to the accompanying drawings.

10 This invention relates to improvement in door locks, and more particularly to a lock of the type that is placed in a mortise or cut-out portion in the edge of a door.

15 The object of the invention is to produce a comparatively simple and efficient lock that is positive in action and durable in construction.

20 With this and other objects in view, my invention consists of certain novel constructions, combinations, and arrangements of parts, as will be hereinafter fully described and claimed.

In the drawings:

25 Figure 1 is a view in side elevation of my improved lock, showing one of the sides of the casing removed.

Fig. 2 is a vertical, sectional view of the lock taken on line 2—2, Fig. 1, looking in the direction of the arrows.

30 Fig. 3 is a view, in side elevation, of the lock bolt.

Fig. 4 is a view in side elevation of the pivotally mounted auxiliary bolt plate.

Fig. 5 is a view in side elevation of the 35 stationary bolt plate.

Fig. 6 is a top plan view of the swinging latch.

Fig. 7 is a view, in edge elevation, of the pivoted link.

40 Fig. 8 is a top plan view of the pivotally mounted weight.

Fig. 9 is a top plan view of the latch-bolt.

Fig. 10 is a front view of the face plate.

Fig. 11 is a front view of the keeper plate.

45 Fig. 12 is a view similar to Fig. 1, showing a spring used in place of the pivotally-mounted weight; the swing latch, however, being shown in Fig. 12 in a locked position.

Fig. 13 is a detail end view showing particularly the operation of the portable key when operating the lock-bolt.

Referring to the drawings by numerals, 1 designates the casing which is of any ordinary construction, and 2 is the shaft or pintle, upon the ends of which are secured the

door knobs 3, Fig. 2. Within the casing 1, and mounted upon the squared portion of the pintle 2 is a sleeve 4 provided with an integral, depending primary lug or finger 5, and the integral, depending auxiliary finger 6 or lug 6. Pivotally mounted on screw 7, and suitably spaced from the sides of casing 1, is a pivoted link 8, which link 8 is provided with a cut-out portion 9, which is engaged by the auxiliary finger 6, and on the side of 65 the link 8 is a laterally-extending lug 10 that is engaged by the primary finger 5, whereby the rotation of the knobs 3 will positively swing link 8 upon its pivot screw 7 to cause the latch-bolt 11, pivotally connected to the 70 link 8, at 12, to be slid inwardly and outwardly upon the casing 1.

A weight 13, provided with a lower flat edge 14, is pivotally mounted, at 15, within the casing 1, so that this weight will always 75 cause the latch-bolt 11 to be extended as shown in Fig. 1 to retain the door upon which my lock is positioned in a locked position within the frame, although a person can easily grasp either one of the knobs 3 and 80 move the latch-bolt into the casing 1 to permit the door to be opened, provided the swinging latch 16 is not moved into the slot 17 of the latch-bolt and into the socket 18 of weight 13, as shown in dotted lines in Fig. 1 85 for locking the latch-bolt from being moved through the medium of the knobs 3; this swinging latch 16 is pivotally mounted, at 19, within the casing 1, and is engaged by the rotatable sleeve 20, which sleeve 20 is 90 provided with lug 21, which lug 21 is adapted to engage and be positioned directly under the swinging latch, as shown in Fig. 12, when the latch is moved into a locked position for causing the latch-bolt to be held in 95 a locked position for preventing the door from being opened through the operation of the knobs 3.

The sleeve 20 is provided with a squared hollow body, and in this squared body is 100 permanently mounted the stationary key 22; by rotating key 22 that has its outer end placed in the room, the lug 21 can be caused to engage the swinging latch (see Fig. 12) and force the outer hooked or angle end of 105 the swinging latch up through aperture 17 of the latch-bolt 11, holding the latch-bolt in the locked position as aforesaid; by rotating the sleeve 20 to the position shown in Fig. 1, the swinging latch 16 will be released, per- 110

mitting the latch-bolt to be freely operated through the action of the operator rotating one of the knobs 3.

In the embodiment shown in Fig. 12, I 5 eliminate the use of weight 13 and in place thereof, I mount, at 23, a spring 24, which spring 24 is provided with an angle end 25 that extends through an elongated slot 26 in the latch-bolt 27 of this embodiment, the 10 spring, by reason of being passed over the securing means 23, will at all times exert an outward stress upon the latch-bolt 27, causing the same to be projected, as shown, sufficiently to lock the door upon which my lock 15 is positioned. Other than the spring 24, this embodiment is similarly constructed to the embodiments illustrated in Figs. 1 and 2.

The lock-bolt device of my lock comprises the sliding lock-bolt 28 that is provided with 20 an elongated, horizontal aperture 29, near its front end, and through this aperture 29 extends a fastening pin 30. Near the inner or rear end of the lock-bolt 28 is a key-receiving slot 31, and on the upper edge of 25 the lock-bolt 28, at 32, is formed a lug. A socket 33 is formed on the inner end of the lock-bolt, and this socket is adapted to receive the fixed horizontal pin or bar 34, which bar 34 is at all times positioned in 30 the socket 35 on the inner end of the stationary bolt-plate 36, which bolt-plate 36 has an aperture 37, and through which aperture 37, pin 30 extends for holding the bolt-plate 36 in a fixed position.

35 A pivotally mounted bolt-plate or tumbler 38 is positioned parallel to the lock-bolt 28 (Figs. 1 and 2) and the pin 30 extends through the aperture 39 to tumbler 38. The tumbler 38 is provided upon its upper edge 40 with a horizontal laterally-extending lug or finger 40, which lug or finger 40 is normally placed in front of the lug 32 on the lock-bolt 28. The stationary bolt-plate 36 is positioned between the pivotally-mounted tumbler 38 and the lock-bolt 28, as clearly 45 shown in Figs. 2 and 13.

The detachable and portable key 41 is positioned in the apertures 42 of the casing 1, and this key is provided with a T-shaped 50 socket 43. The operation of the lock-bolt device is as follows: The key 41 having been placed in the apertures 42 (see Figs. 2 and 13), the key is turned to place the laterally-extending lug 44 of bolt-plate 36 in the T-shaped aperture 43 of the key (Fig. 13), one side of the key riding over the sides of the lock-bolt 28 forming the socket 31, and the other side of the key riding under the lower edge of the pivotally-mounted bolt plate 38. 55 raising the bolt-plate (Fig. 13) so as to cause the extension 40 to be placed above the lug 32 on the lock-bolt 28, and as rotary movement is continued to be imparted to key 41, the key will force the lock-bolt outwardly, and when the key has assumed the 60

position shown in Fig. 2, the extension 40 on bolt-plate 38 will drop behind the lug 32 and thereby securely retain the lock-bolt 28 in its extended position, until the portable key 41 is again inserted in the apertures 42 70 and the key is rotated in the reverse direction for reversing the action returning the lock-bolt into the casing, so to speak, as shown in Fig. 1, for unlocking the lock so far as the lock-bolt device is concerned. 75

In Fig. 10, I have shown the face-plate 45 that is usually placed on the inside of a door; the aperture 46 receiving the pintle 2; the aperture 47 receiving the fixed key 22, and the aperture 48 receiving the key 41. 80

The keeper shown in Fig. 1 is of the ordinary structure, and since it is common to the art, it needs no specific description.

A transverse pin 49 is formed upon the casing 1 for supporting the sliding lock-bolt 85 in an operable position.

I reserve the right to make such alterations and changes to my invention as will be obvious to one skilled in the art to which this invention relates and as shall fairly fall 90 within the scope of the appended claims.

What I claim is:

1. In a lock of the class described, the combination with a casing, of a latch-bolt slidably mounted upon said casing, means 95 for normally holding said latch-bolt in an extended position, a pintle extending through said casing, a sleeve mounted upon said pintle, a link pivotally mounted within said casing, said link provided with a cut-out portion formed upon its upper end and with a laterally-extending lug projecting from one side thereof, and means pivotally connecting the lower end of said link to the inner end of said latch-bolt, said 100 sleeve on the pintle provided with a depending primary finger engaging said lug of the link, said sleeve also provided with an auxiliary, depending finger positioned in the cut-out portion of said link and normally 110 engaging said link.

2. In a lock of the class described, the combination with a casing, of a latch-bolt slidably mounted upon said casing, said 115 latch-bolt provided with an aperture, means for normally retaining said latch-bolt in an extended position, means for drawing said latch-bolt into said casing, a swinging latch pivotally mounted in said casing and provided with an angle end adapted to be positioned in the aperture of the latch-bolt for locking the latch-bolt upon said casing, and means for pivoting said swinging latch for moving the same to a locked position. 120

3. In a lock of the class described, the 125 combination with a casing, of a sliding latch-bolt carried by said casing, means for retaining said latch-bolt in an extended position upon said casing, means for moving said latch-bolt inwardly upon said casing, a 130

swinging latch coöperating with said latch-bolt and adapted to hold said latch-bolt in a locked position upon the casing, a sleeve provided with a hollow body pivotally mounted upon said casing, said sleeve provided with a lug adapted to engage said swinging latch and hold the latch in a locked position, and a key positioned in said hollow sleeve for operating the same for actuating the swinging latch.

4. In a lock of the class described, the combination with a casing, of a lock-bolt slidably mounted upon said casing, a pivotally-mounted bolt-plate positioned parallel to said lock-bolt, said lock-bolt provided with a lug, said pivotally-mounted bolt-plate provided on its upper edge with a laterally-extending lug adapted to fit in front of the lug on the lock-bolt, a stationary bolt-plate provided with a laterally-extending lug positioned between said lock-bolt and said pivotally-mounted bolt-plate, and a key adapted to pass by the lug on said stationary bolt-plate and engage the lower edge of said pivotally-mounted bolt-plate for receiving the same and removing the laterally-extending lug thereof from engagement with the lug on the lock-bolt, for releasing the lock-bolt and permitting the key to slide the lock-bolt upon the casing.

5. In a lock of the class described, the combination with a casing, of a lock-bolt device in said casing, said lock-bolt device comprising a sliding bolt, a pivotally-mounted plate and a stationary plate positioned between said bolt and pivotally-mounted plate, said stationary plate provided with a laterally-extending lug for preventing fraudulent operation of the bolt de-

vice, said pivotally-mounted plate and said bolt provided with means for normally preventing the bolt from sliding upon the casing, and said bolt provided with a socket for receiving a proper key for permitting the key to adjust the bolt upon the casing and at the same time operate the pivoted plate for allowing of the releasing of the bolt for permitting the operation thereof.

6. In a lock of the class described, the combination with a casing, of a lock-bolt device carried by said casing, said lock-bolt device comprising a slideable lock-bolt, said slideable lock-bolt provided near its forward end, with an elongated aperture, and at its rear end with a socket, and with a key receiving socket in its lower edge, a stationary plate positioned parallel to said bolt, said stationary plate provided with an aperture registering with the elongated aperture of said bolt and also provided, at its rear end, with a socket, a pin carried by said casing and positioned in the socket of said stationary plate and normally positioned in the socket on the end of the bolt, a pivoted bolt-plate provided at its forward end with an aperture registering with the elongated aperture in the bolt, fastening means extending through the forward registering apertures of the bolt, stationary plate and pivoted plate, means on the stationary plate for preventing a fraudulent key from operating the bolt device, and means on the bolt and the pivoted plate coöperating for normally preventing sliding movement of the bolt.

In testimony whereof I hereunto affix my signature.

CHARLES A. SHERWIN.
